COMBINED SPOOL BOX AND THREAD CUTTERS

Alvah M. Griffin, Manhattan Beach, Calif., assignor to Reynolds Industries, Incorporated, Santa Monica,
Calif., a corporation of California

Application February 24, 1953, Serial No. 23,741

Term of patent 3½ years

(Cl. D3—19)

Fig. 1

Fig. 2

Fig. 3

Fig. 4

I claim:

The ornamental design for a combined spool box and thread cutters, as shown and described.
